JOSEPH M. MUMFORD, OF SOUTH READING, MASSACHUSETTS, ASSIGNOR
TO HIMSELF AND AUGUSTE F. MASON.

Design No. 3,139, dated July 28, 1868.

DESIGN FOR A TRADE-MARK.

The Schedule referred to in these Letters Patent and making part of the same.

TO ALL PERSONS TO WHOM THESE PRESENTS MAY COME:

Be it known that I, JOSEPH M. MUMFORD, of South Reading, in the county of Middlesex, and State of Massachusetts, have invented or produced a new and original Design for a Trade-Mark; and I do hereby declare the same to be fully represented in the accompanying drawing, and to be described as follows; that is to say, it consists of a horse, and the word "Dexter" arranged between his thigh and shoulder, the whole being as shown in the drawing, in which the horse is shown at a as tied by a halter exhibited at b.

I claim, as my invention or production, the design for a trade-mark as shown and described.

JOSEPH M. MUMFORD.
